DESIGN FOR A DOUGHNUT FORMING APPARATUS

Rudolph F. Petzelt, Chicago, Ill., assignor to Master Doughnut Machine Company, Chicago, Ill., a corporation of Illinois

Application May 14, 1938, Serial No. 77,197

Term of patent 14 years

To all whom it may concern:

Be it known that I, Rudolph F. Petzelt, a citizen of the United States, residing at Chicago, in the county of Cook and State of Illinois, have invented a new, original, and ornamental Design for a Doughnut Forming Apparatus, of which the following is a specification, reference being had to the accompanying drawing, forming a part thereof.

Figure 1 is a plan view of a doughnut forming apparatus embodying my new design;

Figure 2 is an elevational view of the same; Figure 3 is an elevational view taken at right angles to Figure 2; and

Figure 4 is a bottom plan view of the apparatus.

I claim:

The ornamental design for a doughnut forming apparatus, as shown.

RUDOLPH F. PETZELT.
